UNITED STATES PATENT OFFICE.

ERNEST J. POSTAL, OF GRAND RAPIDS, MICHIGAN.

PHONOGRAPH-MOTOR.

1,399,517.

Specification of Letters Patent. Patented Dec. 6, 1921.

Application filed May 22, 1919. Serial No. 299,031.

To all whom it may concern:

Be it known that I, ERNEST J. POSTAL, a citizen of the United States of America, residing at Grand Rapids, in the county of Kent and State of Michigan, have invented certain new and useful Improvements in Phonograph-Motors; and I do hereby declare the following to be a full, clear, and exact description of the invention, such as will enable others skilled in the art to which it appertains to make and use the same.

This invention relates to motors and is particularly concerned with a construction of motor particularly adapted for use in operating the rotating disk carrying-table of phonographs. It is a primary object and purpose of the invention to produce a motor in which an exceptionally large reserve of power may be had so that the motor will operate an exceptionally long time at constant speed without rewinding to replenish the power. A further object of the invention is to provide a novel means for changing the speed of movement of the disk-carrying table and drive the same at different speeds, the motor shaft running at a constant speed. A still further object is to provide a motor shaft which is driven from both sides thereof so that the pressures against the sides thereof are balanced and the only thrust imparted to the shaft is an end thrust which is readily taken care of by a suitable end thrust bearing, this being a feature conducive to greater serviceability of and longer life for the motor. Various other objects and purposes than those specifically mentioned, together with many novel combinations of parts and arrangements thereof to attain the same will appear fully and in detail as understanding of the invention is had from the following description, taken in connection with the accompanying drawings, illustrating the motor, in which drawings,

Figure 1 is a side elevation, with parts broken away, of the motor.

Fig. 2 is a fragmentary sectional view taken vertically between the two spring drums of the motor.

Fig. 3 is a vertical section through one of the spring drums, a fragment of the other drum also being shown.

Fig. 4 is a fragmentary elevation showing one means of control for changing the speed of the table.

Fig. 5 is a view of a detail of structure

relating to the retaining ratchet for the winding shaft of the motor, the parts being shown in side elevation and with portions removed.

Fig. 6 is a plan view of said parts.

Fig. 7 is a horizontal section taken substantially on the line 7—7, of Fig. 1, and

Fig. 8 is a fragmentary elevation and sectional view illustrating a slight modification in the means used for changing the speed of the spindle carrying the disk table.

Like reference characters refer to like parts in the several views of the drawings.

The main support for the motor construction comprises a metal frame 1 having sides and ends and provided with various parts for the attachment of the elements of the motor mechanism which is mainly located within the frame. This frame is ordinarily located below the top 2 of a cabinet, as is usual in phonographs, a spindle 3 to the upper end of which a circular disk carrying table 4 is connected, being mounted vertically in the frame and extending above the top 2 so that the table is practically the only portion of the mechanism disclosed to view. The spindle 3 has a collar 5 a short distance below its upper end which is received in a suitable recess in the frame 1, a plate 6 being attached to the frame above the collar to hold the spindle in place, and any suitable anti-friction bearings being used for the easier operation of the spindle. The spindle at its lower end enters the bored out upper end of a stud 7 threaded through a supporting part 8 of the frame, the end of the spindle being provided with a small ball which rests on a larger ball 9 carried by and within the stud as shown. A friction wheel 10 is splined on the spindle 3 and is provided with a collar 11 to which a yoke 12 is connected, said yoke projecting from a slide 13 mounted for vertical sliding movements in a guide 14 which is formed as an integral portion of the frame and from the lower end of which the supporting arm 8 extends.

A link 15 connects the slide 13 with one end of a lever 16 which is pivotally mounted between its ends, the other end being equipped with a roller 17 which bears against the cam-like end 19 of a cylindrical member 18 mounted to turn about a vertical axis in an indicating disk 20. An operating button 21 is connected to the upper end of the member 18 by means of which the said member may be turned thereby.

changing the position of the lever 16 and of the slide and attached friction wheel, the wheel being moved up or down on the spindle 3. A pointer 22 is attached to the operating button or head 21 extending over suitable indicating characters on the disk 20 and in this manner indicating the speed of the table changed with the change of position of the friction wheel with respect to the friction disk 24 against which the friction wheel bears.

In Fig. 8 a slight modification in the manner of operating lever 16 is shown. The end of said lever is pivotally connected 15 to a pin 17^a rotatably mounted in a sleeve 18^a which has a diagonal slot 19^a cut therein, a pin extending from the pin 17^a through the slot. The indicating disk 20 is formed integral with the sleeve 18^a and the operating 20 head 21 is attached to the upper end of the pin 17^a. This operates to change the position of the friction wheel 10 practically the same as the other construction and is equivalent thereto in all respects. The 25 pointer 22 works in exactly the same way. This indicating disk is attached to the top 2 of the cabinet of the phonograph and the operating head is above the same in ready and convenient position for operation with 30 the indicating disk and pointer easily seen.

The friction disk 24 is fixed at one end of a shaft 25 which is mounted horizontally in the frame 1 in suitable bearings 26 and 27, the latter being an end thrust bearing 35 like that used for the lower end of the spindle 3. Substantially at its central portion a worm 28 is cut on the shaft 25.

At each side of the shaft 25 a spring drum is mounted. Each drum includes a 40 vertical shaft made up of lower and upper sections 29 and 29^a around and loosely mounted on which are upper and lower drum sections 30 and 31 between which a ring 32 is placed the same being permanently attached to the upper drum section 45 30 and formed with a consecutive series of worm teeth to mesh with the worm 28. Within each drum section a strong band spring 33 is placed one end being attached 50 to its respective shaft section and the other to its drum section. It will be noted that both worm gear rings 32 engage with the worm 28 and at directly opposite sides thereof so that there is no tendency for the shaft 55 25 to spring out and away from a worm gear, the pressure normally causing this tendency being equal and opposite on the opposite sides of the worm. Furthermore, the four springs when wound carry a large 60 store of energy which serves to run the shaft 25 and associated parts a relatively long time, much longer than the usual phonograph motor, requiring that the motor be wound but seldom. The thrust bearing at 65 27 receives all of the thrust imparted by

the worm gears and is amply able to take care of it. Of course, a double right and left worm may be used instead of the worm 28 and the end thrust eliminated also if desired.

A worm gear 34 is fixed on the shaft 25 in engagement with a worm 35 which is formed in the length of shaft 36 suitably mounted on the frame 1. A governor 37 of the usual centrifugal type is mounted 75 on and rotatable with shaft 36, the same including a plate 38 which moves with respect to shaft 36 as the governor weights are thrown outward, bringing the same against the end of a brake 39 pivotally mounted on 80 a depending part 40 of the frame, and adjustable to different positions by operation of an adjusting screw 41. This brake is set at the factory and determines the constant speed of the motor shaft 25, any attempted speed above such constant speed bringing the disk 38 against the brake member 39 with a consequent frictional obstruction of the speed until it resumes its normal constant speed.

The springs are wound by turning the lower drum sections of the two drums. A worm gear 42 is attached to the bottom of each lower drum section 31, and a worm 43 on a shaft 44 meshes with each gear 42, as 90 shown. Turning the shaft 44 serves to wind the springs 33 in the lower drum sections 31, and the upper springs in turn are wound by the force of the lower springs transmitted through the shaft sections 29 and 29^a. The end of shaft 44 has a squared portion for the reception of a suitable crank for operating the same. Said shaft 44 has a ratchet wheel 45 fixed thereon just outside of the frame 1 with which a dog 46 100 is adapted to engage to prevent return movement of the shaft. A disk 47 having two projecting annular flanges is also attached to the shaft 44 alongside of the ratchet wheel, and a member 48 is placed 105 around the disk between the flanges, the same being bent to frictionally engage against the flanges as shown in Fig. 6. Member 48 extends from the disk at one point and engages with a pin 49 on the 110 dog 46, being slotted at 50 to pass over the pin. When the shaft 44 is turned to wind the springs, the frictional engagement of member 48 with the flanged disk 47 has a 115 tendency to turn member 48, and the angle 120 of the sides of the slot 50 is such that such turning movement moves the dog 46 outward just beyond the ends of the ratchet teeth and the winding is accomplished without noise of the dog passing over the ratchet 125 wheel. The dog returns by spring pressure to holding position when the turning of the shaft 44 is stopped. The outward movement of the dog 48 may be stopped in any suitable manner after it is out beyond the 130

range of the teeth of the wheel 45 and before the member 48 entirely disengages from pin 49.

A housing 51 is attached to the member 14 of the frame, as shown in Fig. 7 in which a rod 52 is slidably mounted, being spring actuated by a spring 53 so that the end of the rod presses against the slide 13. The spring is located between a collar on the 10 rod 52 and a closing cap 54 for the housing. In this manner the friction wheel 10 is maintained with steady and uniform pressure against the friction disk, and compensates for any wearing of the two friction 15 members which may occur.

The construction of the motor described is one noiseless in operation, one in which the winding of the same has to be done but infrequently, and one in which the different 20 speeds for the disk carrying table may be easily and noiselessly effected by friction transmission between the constant speed motor shaft and the spindle carrying the table. In this connection it is evident that 25 if a spring should have any tendency to stick in its unwinding, the other springs will operate to at once overcome such tendency and there will not be any of the noises of release of a spring where one only is used. 30 In order for this to occur it will be necessary for all four of the springs to stick together at the same time, a practically impossible occurrence. Moreover there is no diminution of power at any time to run the shaft 25, for 35 if a spring in one of the drums should stick, the other one in the same drum will act and at the same time the other drum on the opposite side of the shaft will continue to operate under full force, at once compelling 40 the spring which sticks to release and continue its work. The large store of power in the four springs makes the winding of the device necessary only at long intervals. The construction is relatively simple and 45 economical to make and it can be produced at a comparatively low cost of manufacture. The motor is very effective for the purposes for which it is designed and has proven satisfactory in all respects in actual and 50 severe tests.

I claim:

1. A motor including a supporting frame, a shaft mounted horizontally on and within the frame, said shaft having a worm formed 55 at one point in its length, a drum mounted to turn about a vertical axis at each side of the shaft, each drum comprising an upper and a lower drum section with a ring interposed between the same, said ring being

formed as a worm gear at its outer edges, 60 and said worm gears meshing with the worm at opposite sides thereof, a spring within each drum section, means to simultaneously wind all of the springs, and mechanism driven by the shaft, substantially as de- 65 scribed.

2. A motor comprising a supporting frame, a shaft located horizontally and mounted for rotation in the frame, said shaft having a worm formed in its length 70 between its ends, a drum located at each side of the shaft, a worm wheel on each drum meshing with the worm at opposite sides thereof, a shaft extending vertically through each drum and on which each drum is rotatably mounted, a spring in each drum attached at one end to the shaft and at the other end to the drum, a winding shaft mounted on the frame, gears thereon, one for each drum, gearing connections between 80 the drums and said gears, and means for holding the winding shaft in any position to which it is turned against return movement, substantially as described.

3. A motor comprising a supporting frame, a shaft mounted horizontally thereon for rotation, a worm formed on the shaft between its ends, a drum mounted to turn about a vertical axis at each side of the shaft, a worm gear on each drum meshing with the worm at opposite sides thereof, spring means housed within the drums for normally turning the same about their respective vertical axes, means for winding the said spring means in both drums simultaneously, a worm gear on the shaft, a governor shaft mounted on the frame, said shaft having a worm in its length with which said last mentioned gear engages, a governor on the governor shaft operable to 100 maintain the first shaft at constant speed of rotation, and mechanism driven by said first shaft, substantially as described.

4. A motor including a horizontally mounted drive shaft, said shaft having a worm formed in the length thereof, a friction disk connected to one end of the shaft, spring drums mounted one at each side of the shaft, each drum carrying a worm gear in mesh with the worm at opposite sides 110 thereof, means for winding the drums to tension the springs therein, a vertically mounted spindle, a friction wheel splined thereon and in frictional engagement with the friction disk, and means for changing the 115 position of the friction wheel on the spindle.

In testimony whereof I affix my signature.
ERNEST J. POSTAL.
